UNITED STATES PATENT OFFICE

RICHARD McKNIGHT, OF CHICAGO, ILLINOIS.

FILING DEVICE.

1,421,515.

Specification of Letters Patent.

Patented July 4, 1922.

Application filed February 12, 1921. Serial No. 444,394.

To all whom it may concern:

Be it known that I, RICHARD McKNIGHT, a citizen of the United States, and a resident of the city of Chicago, county of Cook, and 5 State of Illinois, have invented certain new and useful Improvements in Filing Devices, of which the following is a specification.

My invention relates to improvements in filing devices, the present invention constituting an improvement on the invention disclosed in my prior Patent No. 1,171,529 granted me on February 15, 1916 for filing devices. The object of the present invention is to provide an improved arrangement 15 especially adapted for applying the devices set forth in said patent and more especially an arrangement whereby such a device may be readily applied to a filing cabinet or receptacle not especially designed for such 20 use.

Other objects will appear hereinafter.

The invention consists in the combinations and arrangements of parts hereinafter described and claimed.

25 The invention will be best understood by reference to the accompanying drawing forming a part of this specification, and in which,

Fig. 1, is a perspective view illustrating 30 a construction embodying the invention in position of use,

Fig. 2, an enlarged detailed perspective view illustrating a section of one edge of the filing tray or drawer illustrated in Fig. 1,

35 Fig. 3, a perspective view of one of a plurality of channel members employed in the construction,

Fig. 4, a perspective view of one of a plurality of supporting clips employed in 40 the construction,

Fig. 5, an exterior elevation of an upper corner of the filing tray or drawer,

Fig. 6 a view similar to Fig. 4, but showing a slightly modified form of supporting clip,

Fig. 7, a transverse section through the side of a filing drawer or tray showing the clip illustrated in Fig. 6 in position of use,

Fig. 8, an exterior elevation of the construction illustrated in Fig. 7, and

Fig. 9, a similar view, with portions broken away, showing the opposite end of the drawer or tray.

The form of construction illustrated in 55 Figs. 1 to 5 inclusive, comprises a plurality of supporting clips 10 made of sheet metal

and substantially Z-shaped in cross section, each clip being provided at its bottom with an inwardly and upwardly bent supporting lip 11 forming a narrow supporting channel 60 as shown. At its upper end each of the clips 10 is provided with an outwardly and downwardly turned lip or flange 12 forming a wide supporting channel adapted and arranged to fit over the edges of the filing 65 drawer or tray 13. The form of tray illustrated is made of sheet metal provided at its upper edges with the usual reenforcing beads or lips 14 whereby said tray is sufficiently stiffened and straightened longitudinally to serve its purpose. In order to render the engagement with this bead a stable one, I provide channel members 15 adapted to fit over said bead and rest against the outer side of the tray, the clamping jaw 70 12 of the clip fitting snugly over said channel member as best shown in Fig. 2. By this arrangement the clips 10 may be readily applied to the sides of a sheet metal drawer or tray and securely held in place with the 80 supporting lips 11 positioned against the inner surfaces of the sides thereof, two of said clips being applied to each side of the tray as indicated in Fig. 1.

Longitudinal guide members 16 are 85 mounted to extend along the tops of the sides of the tray 13. These guide members are made of sheet metal in channel form and provided with depending aprons or supporting flanges 17 adapted to snugly fit behind the lips 11 with the bodies of the guide members resting on the tops of the clips 10. By this arrangement it will be observed that the guides 16 may be readily applied to any ordinary sheet metal tray or drawer. 95

Each of the guide members 16 is provided with an open guide slot 18 adapted to receive the hook projections 19' of supporting bars 19 adapted and arranged to support the flexible strip or apron 20 constituting the filing element proper as set forth in my said prior patent. This arrangement constitutes a simple and effective arrangement for guiding the supporting bars 19 and permitting of their ready attachment to or detachment from the tray, said supporting bars being readily removed from the guides when desired as indicated by the dotted lines in Fig. 2.

Each of the guide members 16 is provided at each end thereof with a downwardly and inwardly turned lug or ear 21

- arranged to limit the movements of the bars 19 and prevent their accidental displacement from the ends of said channel members.
5. The modified form of construction illustrated in Figs. 6 to 9 inclusive is identical with that already described except that the arrangement is such as to be attached to a wooden drawer or tray instead of a sheet metal drawer or tray. To this end the clips 10' are provided with perforated flanges 22 adapted and arranged to rest over on the tops of the tray sides and secured in place by screws 23. Otherwise the construction is 15 identical with that already described and needs no further description.
- While I have illustrated and described the preferred form of construction for carrying my invention into effect, this is capable of variation and modification without departure from the spirit of the invention. I, therefore, do not wish to be limited to the precise details of construction set forth, but desire to avail myself of such variations and 25 modifications as come within the scope of the appended claims.
- Having described my invention, what I claim as new and desire to secure by Letters Patent is:—
- 30 1. The combination with a filing receptacle, of supporting clips fitting over and detachably engaging the sides thereof; and guides detachably supported by said clips, substantially as described.
- 35 2. The combination with a filing receptacle, of supporting clips fitting over and detachably engaging the sides thereof; upwardly turned supporting lips on said clips forming channels; and guides provided 40 with supporting means fitting said channels, substantially as described.
3. The combination with a filing receptacle, of supporting clips substantially Z-shaped in cross section, said clips being provided 45 at their tops with outwardly extending channels adapted to fit snugly over the
- sides of said receptacle and at their bottoms with upwardly turned supporting lips forming channels; and guides provided with supporting means snugly fitting said 50 supporting channels, substantially as described.
4. The combination with a filing receptacle, of supporting clips fitting over and detachably engaging the sides thereof; and guides detachably supported by said clips, said guides being provided with stops at their ends, substantially as described.
5. The combination with a filing receptacle, of supporting clips secured to the 60 sides thereof; upwardly turned supporting lips on said clips forming channels; and sheet metal guides adapted to rest upon the tops of said clips and provided with depending flanges snugly fitting said channels, said guides being provided with inwardly turned stop plugs at their ends, 65 substantially as described.
6. The combination with a sheet metal receptacle having a reenforcing bead at its 70 upper edges, of a channel member fitting over said bead and resting against the side of said receptacle; and a clip fitting over said channel member, substantially as described.
7. The combination with a sheet metal receptacle having a reenforcing bead at its 75 upper edges, of a channel member fitting over said bead and resting against the side of said receptacle; a clip substantially Z- shaped in cross section provided at its top 80 with a downwardly extending clamping jaw fitting over said channel and at its bottom with an upwardly extending supporting lip, substantially as described.
- In testimony whereof, I have signed my name to this specification in the presence of one subscribing witness.
- RICHARD McKNIGHT.
- Witness:
- FREDA C. APPLETON.
